DETERMINATION OF ASPHALTIC COMPONENTS OF PETROLEUM

Rollie B. Williams and Rhoderick K. Saunders, Baytown, Tex., assignors, by mesne assignments, to Esso Research and Engineering Company, Elizabeth, N.J., a corporation of Delaware

Application November 14, 1957, Serial No. 696,362

6 Claims. (Cl. 208—309)

This invention relates to a method for determining the quantity of asphaltene type hydrocarbons contained in a sample. More particularly, this invention relates to a method for quantitatively determining the asphaltenes content of a sample of a petroleum hydrocarbon fraction and to a method for regulating a process for treating the hydrocarbon fraction in response to the determination.

Petroleum crude oils and many petroleum hydrocarbon fractions are characterized by the presence of high molecular weight asphaltenes. Such asphaltenes are undesirable feed components for many hydrocarbon treating processes, such as hydrocarbon cracking processes, and therefore are desirably excluded from the feed stock by suitable means such as fractional distillation, deasphalting, etc.

Asphaltic hydrocarbon components tend to be insoluble in light hydrocarbon fractions such as paraffinic naphtha fractions and therefore asphaltene hydrocarbon determinations are normally made on the basis of time-consuming solubility tests.

It has been discovered in accordance with the present invention that when an asphaltenes-containing petroleum hydrocarbon sample is subjected to electron paramagnetic resonance spectroscopic analysis, there is obtained a signal having an intensity responsive to the quantity of asphaltene components in the sample. The electron paramagnetic resonance spectroscopic determination of the present invention is easily conducted with electron paramagnetic resonance spectrometers of conventional construction which are operated in the manner well known to those skilled in the art. Instrument construction and operating techniques are discussed, for example, in an article by John E. Wertz (Nuclear and Electronic Spin Magnetic Resonance, Chemical Reviews, 55, 829 (1955)) and in publications annotated in the Wertz article.

ELECTRON PARAMAGNETIC RESONANCE DETERMINATIONS OF ASPHALTENES CONTENT

Sample No.	Nature of Sample	Asphaltenes Content, Wt. Percent ¹	Concentration of Sample in Sample Tube, Gms./cm. Length	Peak Height Prior to Adjustment (Chart Div.)	Relative Attenuation	Adjusted ² Peak Height (Chart Div.)	Absorptivity ³
1.....	West Texas Residuum.	6.87	0.1109	16.0	3.8	60.8	548
2.....	Deasphalted Oil.....	0.08	0.1132	1.3	1.0	1.3	11

¹ By standard solubility test.

² Adjusted peak height = original peak height $\times$ attenuation.

³ Absorptivity = $\frac{\text{Adjusted peak height}}{\text{Concentration}}$

In accordance with a preferred form of the present invention, the electron paramagnetic resonance determina-

tion is made under standardized predetermined operating conditions with a spectrometer of predetermined standardized construction whereby the intensity of the signal that is obtained provides a direct quantitative determination of the asphaltenes content of the sample. The determination may be made while the sample is in a solid, semi-solid, or liquid condition. It is preferable to dilute the asphaltenes-containing sample with an amount of a low boiling solvent sufficient to provide a solution containing a predetermined amount of sample, such amount preferably being less than about 10% by volume.

In accordance with a preferred form of the present invention, a continuous process for the treatment of an asphaltenes-containing petroleum hydrocarbon fraction is regulated by periodically or continuously sampling a treating process hydrocarbon stream, by determining the asphaltenes content of such samples and by continuously regulating a treating process variable in response to such determination.

The present invention will be further illustrated by the following specific examples and by the accompanying drawings which are given by way of illustration and which are not intended as limitations on the scope of the invention.

In the drawings:

Fig. 1 is a graph showing the interrelationship of electron paramagnetic resonance signal intensity, with respect to asphaltenes content, as demonstrated by the data of Example I; and

Fig. 2 is a schematic diagram indicating one manner in which a process for treating an asphaltic hydrocarbon may be regulated in accordance with the present invention.

EXAMPLE I

A plurality of deasphalted oil samples and residuum petroleum samples were subjected to electron paramagnetic resonance spectroscopic analysis on a spectrometer operated at a frequency of about 9200 megacycles at a magnetic field strength of about 3000 gauss. The samples were contained in thin cylindrical glass tubes of about 5 mm. outside diameter. The samples tested and the results obtained are set forth in Table I. The results are further graphically presented in Fig. 1.

Table I

ELECTRON PARAMAGNETIC RESONANCE DETERMINATIONS OF ASPHALTENES CONTENT

From Table I and Fig. 1, it is seen that there is a correlation between electron paramagnetic resonance signal intensity and asphaltenes content whereby a direct quantitative measurement of asphaltenes content may be made.

The manner in which a petroleum hydrocarbon treating process may be regulated in accordance with the present invention is illustrated with reference to Fig. 2.

Turning next to Fig. 2, there is shown a treating zone 10 for treating an asphaltic petroleum hydrocarbon fraction. Treating zone 10 may be, for example, a solvent deasphalting zone for deasphalting an asphaltic hydrocarbon feed stock with a solvent such as a liquefied normally gaseous hydrocarbon, liquefied sulfur dioxide, etc. to obtain a deasphalted oil suitable for catalytic cracking, a distillation zone for separating an asphaltenes-free distillate fraction from an asphaltic feed stock, a blending zone wherein an asphaltic hydrocarbon fraction derived from a petroleum refining process (e.g., catalytic cracking, distillation, etc.) is blended with a non-asphaltic fuel oil fraction to provide a furnace fuel, etc.

An asphaltenes-containing hydrocarbon feed stock is charged to the treating zone 10 by way of a charge line 12 regulated by suitable means such as an electrically or pneumatically actuatable valve 14. Although only a single charge line for the treating zone 10 is shown in Fig. 2, it will be understood that in practice one or a plurality of charge streams may be charged to the treating zone 10, depending upon the particular treating process to be conducted therein. A treating process product stream is discharged from the zone 10 by way of a line 16. It will be understood that in many processes a plurality of discharge streams (not shown) may be discharged from the treating zone 10.

In accordance with the present invention, the product stream 16 is sequentially sampled (on an intermittent or continuous basis) by way of a sample line 18 controlled by a valve 20 leading to an analysis zone 22. If desired, a suitable solvent may be blended with the sample in the line 18, the solvent being charged by way of a line 24 controlled by a valve 26.

The sample material, after analysis, may be discharged from the analysis zone by way of the discharge line 30 controlled by a valve 32 for discharge from the system or alternately, for example, may be returned to the discharge line 16 by way of a line 34 controlled by a valve 36.

The electron paramagnetic resonance absorptivity of the samples is measured in the zone 22 and a signal constituting a measurement of asphaltenes content is obtained which is transmitted by way of a lead 28 to a suitable process variable control means such as the actuating means for the value 14. If the intensity of the signal transmitted through the lead 28 falls outside of a predetermined signal intensity range, the setting of the valve 14 will be changed by actuating of the control means to thereby provide for the desired treating conditions in the zone 10.

As a specific example, the treating zone 10 may be a deasphalting zone wherein a hydrocarbon residuum fraction is treated with a liquefied normally gaseous hydrocarbon solvent under conditions of temperature, contact time, and solvent-to-oil ratio sufficient to provide for the obtaining of a deasphalted oil fraction suitable for catalytic cracking and an asphalt fraction.

In a typical solvent deasphalting operation it may be desirable to regulate deasphalting operations in a manner

to provide for the presence of from about 0.1 to 1 weight percent of asphaltenes in the deasphalted oil, this being done in order to insure the recovery of a maximized amount of useful non-asphaltic components or to exclude a maximized amount of asphaltic components. In this situation, the asphaltenes content of the discharge stream 16 is sequentially determined (on a continuous or intermittent basis) and if the asphaltenes content falls either above or below the predetermined range, a deasphalting process variable may be altered in response to determination to provide for the desired asphaltenes content. Among the deasphalting process variables that may be regulated are solvent-to-feed stock ratio, temperature, solvent composition, etc.

Having described our invention, what is claimed is:

1. A method for determining the asphaltenes content of an asphaltic petroleum hydrocarbon sample which comprises measuring the electron paramagnetic resonance absorptivity of said sample to thereby obtain a measurement of the asphaltenes content of said sample.

2. A method for determining the asphaltenes content of an asphaltic hydrocarbon sample which comprises dissolving said sample in a non-ionic organic solvent and then measuring the electron paramagnetic resonance absorptivity of said sample to thereby obtain a measurement of the asphaltenes content of said sample.

3. In a process for continuously treating an asphaltic hydrocarbon feed stock, the improved method for regulating said treating process which comprises the steps of sequentially sampling a treating process stream, sequentially measuring the electron paramagnetic resonance absorptivity of the thus-obtained samples under predetermined analysis conditions and controlling a hydrocarbon treating process variable in response to said measurement.

4. A process as in claim 3 wherein the treating process is a solvent deasphalting process.

5. In a process wherein an asphaltic petroleum hydrocarbon feed stock is deasphalting by contact with a liquefied normally gaseous hydrocarbon to separate said feed stock into an asphaltic fraction and a deasphalted oil fraction, the improved method for regulating said deasphalting operation which comprises the steps of sequentially sampling said deasphalted oil fraction, sequentially subjecting said samples to electron paramagnetic resonance spectroscopic analysis to obtain an electrical signal constituting a measurement of the asphaltenes content of said samples and electrically regulating a deasphalting process variable in response to said signal.

6. A process as in claim 5 wherein the ratio of liquefied normally gaseous hydrocarbon to asphaltic feed stock is regulated in response to the signal.
